8 Claims.

(Cl. 68—18)

The present invention relates to the treatment of raw wool and more particularly to an apparatus for removing grease, oil, and dirt or other foreign substances from raw wool by use of solvents, and for collecting and separating dirt from the solvent.

In the treatment of raw wool as heretofore carried out it has been the practice to load a batch of wool into a kier for treatment by a suitable solvent, after which the wool is removed for a scouring operation. This latter consists of passing the wool through a series of wash tanks containing soap and soda ash so that all water soluble material together with dirt and other foreign substances are worked out of the wool. The solvent treatment not only takes time but since the packed wool functions as a filter only grease and oil are removed, while dirt remains in the wool and has to be extracted by the scouring operation. In packing the wool into the kiers, it is necessary for laborers to be inside of the kier to receive and pack the wool and also to remove it after the solvent treatment. This is not only a hot, disagreeable task but hazardous while working in the fume-filled kier.

Some of the objects of the present invention are to improve the present apparatus for treating raw wool; to provide an apparatus which eliminates the use of soap and soda ash for the removal of dirt and other deleterious substances; to provide an apparatus wherein it is possible to remove oil, grease and dirt simultaneously from raw wool; to provide an apparatus wherein provision is made for separating and collecting dirt from solvent which has traversed a mat of raw wool; to provide means for extracting and recovering solvent used in the heating of raw wool; to provide means for causing a mat of raw wool to move in a predetermined path and be subjected to a stream of solvent and to be thereafter subjected to a stream of heated air to extract therefrom contained solvent; to provide improved solvent extracting and reclaiming means in the treatment of raw wool; and to provide other improvements as will hereinafter appear.

In the accompanying drawings Fig. 1 represents a plan of one end portion of wool processing apparatus embodying one form of the present invention; Fig. 1-A represents a plan of the other end portion of the apparatus, the same being a continuation of Fig. 1; Fig. 2 represents a side elevation, partly broken away, of that portion of the apparatus shown in Fig. 1; Fig. 2-A represents a side elevation of that portion of the apparatus shown in Fig. 1-A; Fig. 3 represents a section on line 3—3 of Fig. 4; Fig. 4 represents a section on line 4—4 of Fig. 1; Fig. 5 represents a section on line 5—5 of Fig. 6; and Fig. 6 represents a detail in plan of one of the solvent col-

lecting tanks the cover being removed to show the interior construction.

Referring to the drawings one form of the present invention consists of a trough or way 10 of generally U-shape in transverse section throughout the major portion of its length and horizontally mounted upon a skeleton frame 11, of structural steel or other suitable material. The side walls of the trough 10 are solid while the bottom is formed by a grating or reticulated plate 12. The trough 10 forms an open top conduit through which raw wool, or other fibrous material, is fed into position for such treatment as will remove grease, oleaginous substances, dirt and other foreign matter as a preliminary to the finishing operations. The length of the trough 10 depends upon the number of processing steps, so that the complete apparatus consists of a plurality of units, each of which includes a section 15 of the trough 10. In the present instance the apparatus shown by way of example includes several units, A, B, and C, for solvent treating, and several units, D, E, and F, for drying treatment, and to avoid repetition only one unit of each series will be described but like reference numerals applied to like parts in the other units as deemed necessary.

In order to feed wool into the trough 10, a hopper 13 is mounted upon the frame 11 and has its discharge in communication with the receiving neck 14, of the trough 10, which projects through the end wall of the casing 15. This casing 15 encloses the parts forming the first unit A of the solvent treating means, and is arranged to be connected to an adjacent unit B so that a series of units can be assembled as required to take care of as many processing steps as may be found necessary. This receiving neck 14 of the trough 10, while being a continuation of the trough proper, has a solid bottom and a solid top except for the outlet from the hopper 13. One end of the neck 14 receives a piston 16 while the other end opens directly into the trough 10. The neck 14 thereby forms a tubular passage into which the wool is discharged from the hopper 13, where it is met by the piston 16, and is pushed forward through the neck 14 into the trough 10. This tubular construction of the neck 14 is important because it causes the wool to be compressed or well packed at the entrance to the trough 10, and in this way seals the inlet so that fumes from the solvent cannot escape. A similar seal is made possible at the discharge end of the trough 10, by constructing the protruding end 17 of the trough 10 in the form of a tube tapering to the outlet. Hence as the wool reaches this tubular portion enough back pressure is developed to cause sufficient packing of the wool as will seal the outlet against the escape of fumes and processing odors.

For reciprocating the piston 16, it is formed as an extension part of a carriage 18, supported by wheels 20 respectively riding in pairs upon side rails 21 carried by the frame 11. Connecting rods 22 attached respectively to opposite sides of the carriage 18 join cranks 23 of shaft 24, which latter is journaled on the frame 11 and rotated by suitable power transmitting means such as a belt and pulleys from a motor 25.

In order to cause the wool 26 to travel through the trough 10, a plurality of rake tines 27 are attached to a shaft 28 and depend therefrom to terminate in close proximity to the bottom of the trough 10. This shaft 28 extends transversely above the trough 10 and is journaled for oscillation in ears fixed to and extending from a cross-bar 31, which has its ends respectively fastened to two carrier angle plates 32. Reciprocable drive rods 33 respectively join the plates 32 to the carriage 18, so that movement of the latter causes the proper reciprocating stroke of the plates 32. The plates 32 seat respectively upon stationary rollers 34 which are journaled on ball bearings 35, the latter being supported by and laterally projecting from the frame 11. The shaft 28 is provided with stop lugs 36 arranged to engage the bar 31 so that the tines 27 are held rigid on the working stroke but permit the tines 27 to swing forwardly upon the return stroke in order to assume another wool pushing stroke. While the foregoing describes only a single series of tines 27, it is preferable to employ several of these series of tines in each unit, the shafts 28 of which are spaced in parallel and are connected to and operated by the reciprocating frame of which the carrier plates 32 are the main parts. In order that these tine assemblies can be easily reached for adjustment, repair or replacement, the side walls of the casing 15 are provided with hand holes having removable covers 37 conveniently located for the purpose.

In order to subject the wool to the action of the degreasing solvent, a set of spray nozzles 38 are provided and hang in pairs from a header 40 attached to the top of the casing 15. The lower end of each nozzle 38 carries a stirrup 41 for supporting a V-shaped baffle 42, and the length of the nozzle 40, stirrup 41 and baffle 42, is such that the lower end of the baffle is just above the plane of the bars 31. It should be noted, however, that transversely adjacent stirrups are angularly disposed with respect to each other and, therefore, the discharged solvent is deflected in different directions from the baffles to ensure a complete spread over the top area of the wool 26. The header 40 is supplied with solvent from a pump 44 having an inlet pipe 45 communicating with a closed top collection tank 46 at a point well above the sediment level. This tank 46 collects the dirt and grease-filled solvent after it has passed through the wool, and for that purpose communicates, by way of a pipe 47, with a return duct 48 to which the drained solvent is directed by an inclined partition 50 extending transversely across the unit below the grating 12 of the trough 10. The duct 48 also extends across the unit parallel to the lower edge of the partition 50 and is open at its top to receive the flow discharged across the partition. Within the duct 48 there is a filter 51, preferably of V-section, arranged to intercept the solvent as it leaves the partition 50, and thereby prevent fine wool fibres from being carried into the collecting tank 46. As shown the tank 46 has a bottom formed by walls con-

verging downwardly to an apex in the form of a transverse gutter 52 having a screw conveyor 53 rotatably mounted therein for feeding the returned solvent along the gutter 52 and into a conduit 54; which, as shown, rises vertically and has an angularly disposed discharge pipe 55. In the case of adjacent collecting tanks 46, this pipe 55 leads from one to another until the end tank 46 is reached and there the pipe 55 discharges into a dirt and solvent receiver 56. From the receiver 56 a discharge pipe 57 leads to a pump 58 which serves to deliver the solvent and dirt to a suitable recovery system. It should be noted that the pipe 47 from the duct 48 enters the tank 46 near the discharge end of the gutter 52. Also, a partition 61 rises vertically above the conveyor 53 to divide the tank 46 longitudinally for the major portion of its length.

For the purpose of extracting residual solvent 20 from the wool following its travel through the several solvent units, the trough 10, with its tines and reciprocating carrier, enters and passes through a chamber 62 formed by an enclosing casing 63. Within this chamber 62 are the plurality of heater units D, E and F, each of which consists of a coil of heater pipes 64 contained in a compartment 65 having an inlet 66 and an outlet 67, the former communicating with an air supply duct 68 and the latter opening in juxtaposed relation to the upper surface of the wool in the trough 10. The duct 68 communicates with the discharge of a blower 70 which draws in air from the chamber 62, and thus establishes a circulation through the heater coils, the wool, the chamber 62, the blower 70, and the duct 68. Since this air becomes saturated with solvent extracted from the wool, it is desirable to provide a condenser 71 through which the air from the chamber 62 can be circulated. For this purpose the duct 68 of unit D has a by-pass 72 leading to the condenser 71 and controlled by a gate 73 which can be adjusted at will to meet conditions of saturation. Also, the condenser 71 communicates by a conduit 74 with the end unit F in order to circulate solvent-filled air from that end of the chamber 62 into the condenser 71, where all condensed solvent is collected ready to be drawn off and reclaimed.

50 In the operation of the apparatus raw wool is discharged from the hopper 13 and enters the inlet neck 14 where the reciprocating piston 16 pushes it into the trough 10 where the feed tines 27 of unit A are operative to pass the wool along the trough. Thus a mat of wool is formed which is caused to travel the length of the trough to leave the discharge end cleaned of oil, grease and dirt. The mat thickness is such as will allow the dirt to be flushed out by the solvent, and no filtering action takes place. A thickness averaging an approximate four inches will fulfill this condition. As the mat travels along it is being continuously supplied with wool from the hopper so that, in effect, it is a continuous mat throughout the length of the apparatus. As the wool mat passes through the casings 15, it is successively subjected to a solvent spray from the nozzles 38, and this solvent flushes through the mat to discharge through the grating plate 12 into the collecting tank 46. The solvent may be any one of many well known for the purpose, such as carbon tetrachloride, trichlorethylene, or any other non-inflammable mixture. The major portion of the dirt is removed while passing through the unit A, and there is less and less in the suc-

ceeding units, until practically a clean wool leaves the last of the solvent treating units. The mat now passes through the series of heating units D, E and F, where heated air traverses the mat to pick up solvent vapor and thereby leave the wool substantially free from residual solvent. This vapor-filled air is circulated to a condenser 71 for reclaiming the solvent in liquid form.

While in the foregoing it may appear that all oil and grease has been removed from the wool, such complete removal is not desired because enough oil should be left in the wool to prevent the fibres from becoming brittle. Where all the grease is extracted by the present process it then becomes necessary to add an amount of oil to the wool in the correct percentage to condition the wool for finishing. To take care of this situation, it is contemplated to employ a measuring device to control the percentage of grease as the wool leaves the apparatus. Devices of this character are available in the market and function to automatically maintain the desired percentage of grease or oil in the wool.

Further, it should be noted that the flow of used solvent is counter to the direction of travel of the material so that the collecting tank 46 at the discharge end of the solvent treatment receives the cleanest solvent, and from which the solvent flow progressively increases in the percentage of contained grease and dirt until the last tank of the series is reached. It should also be noted that while the construction shown includes a trough having a perforate bottom, the invention is not limited to such precise construction and any suitable support of a pervious character can be used for the wool. The term "pervious" meaning such a construction as will permit solvent to pass therethrough with contained dirt but prevent the passage of wool fibres.

Having thus described our invention, we claim:

1. An apparatus for treating raw wool, comprising a chamber, a support passing through said chamber and projecting from said chamber to form an inlet passage for loose wool fibres, that portion of said support within said chamber having a perforate bottom, a hopper for delivering said fibres to said inlet, means operating in said passage to compress said fibres to seal said inlet against fumes escaping from said chamber, means to feed said fibres along said support in the form of a mat, and means above said support to deliver a solvent for passage through said mat and perforate bottom to flush oleaginous substances and dirt from said mat.

2. An apparatus for treating raw wool, comprising a chamber, a support passing through said chamber, an inlet passage for loose wool fibres leading to said support, said support having a perforate bottom, a hopper for delivering said fibres to said inlet, means operating in said passage to compress said fibres to seal said inlet against fumes escaping from said chamber, means to feed said fibres along said support in the form of a mat, means above said support to deliver a solvent for passage through said mat and perforate bottom to flush oleaginous substances and dirt from said mat, and means below said perforate support for collecting dirt flushed from said mat.

3. An apparatus for treating raw wool comprising a chamber, a support passing through said chamber and having a perforate bottom, a hopper for raw wool, means for feeding said wool from said hopper into said support, means in-

cluding a reciprocable plunger and a plurality of reciprocable tines for feeding said wool along said support in the form of a mat, said plunger functioning to compress and move said wool into said position for engagement by said tines, and means above said support to deliver a solvent for passage through said mat and perforate bottom to flush oleaginous substances and dirt from said mat.

4. An apparatus for treating raw wool, comprising a chamber, a support passing through said chamber and having a perforate bottom, a hopper for raw wool having a bottom discharge outlet, means movable transversely of said outlet for feeding wool from said hopper onto said support, means for keeping said wool moving on said support and preventing packing under the action of said feeding means, and means in said chamber to deliver a solvent for passage through said wool and perforate bottom to flush oleaginous substances and dirt from said wool.

5. An apparatus for treating raw wool, comprising a treating chamber, means to feed raw wool in mat form through said chamber, spray means to subject the wool successively to streams of solvent as the wool passes through said chamber, a plurality of solvent collecting chambers below said wool into which used solvent is discharged, said collecting chambers being successively at lower levels in the direction of the inlet end of said chamber, over-flow pipes from each collecting chamber to the next adjacent, and means in each collecting chamber to feed collected dirt-impregnated solvent to the next adjacent collecting chamber.

6. An apparatus for treating raw wool, comprising a chamber, a support passing through said chamber, an inlet passage for loose wool fibres leading to said support, said support having a perforate bottom, means to deliver said fibres to said passage means operating in said passage to compress said fibres to seal said inlet against fumes escaping from said chamber, means synchronized with said compressing means to feed said fibres along said support in the form of a mat, means above said support to deliver a solvent for passage through said mat and perforate bottom to flush oleaginous substances and dirt from said mat, and means below said perforate support for collecting dirt flushed from said mat.

7. An apparatus for treating raw wool, comprising a treating chamber having an inlet and an outlet, a hopper for delivering raw wool to said inlet, a reciprocable plunger, means for operating said plunger to deliver wool from said hopper to said inlet, means operating upon said wool between said inlet and said outlet to prevent packing of said wool and thereby maintain a substantially uniform thickness of the wool mat as propelled by said plunger, and solvent discharging sprays above said mat.

8. An apparatus for treating raw wool comprising a treating chamber having an inlet and an outlet, a hopper for delivering raw wool to said inlet, a reciprocable plunger, a plurality of rake tines mounted between said inlet and outlet, solvent discharging sprays above said trough and the wool thereon, and means for simultaneously operating said plunger and rakes, whereby the wool is fed into mat form and prevented from packing throughout its length.
